(57) **CLAIM**

(**) Term: **15 Years**

The ornamental design for a rear combination lamp for an automobile, as shown and described.

(21) Appl. No.: **29/612,070**

DESCRIPTION

(22) Filed: **Jul. 28, 2017**

FIG. 1 is a front elevational view of a rear combination lamp for an automobile in accordance with a first embodiment of our new design;

(30) **Foreign Application Priority Data**

FIG. 2 is a rear elevational view thereof;

Feb. 7, 2017 (JP) 2017-002157

FIG. 3 is a top plan view thereof;

(51) **LOC (11) Cl.** **26-06**

FIG. 4 is a bottom plan view thereof;

(52) **U.S. Cl.**

USPC **D26/28**

(58) **Field of Classification Search**

USPC D26/28-36; 362/80-83, 267-269,

362/459-468, 475-478, 485-487

FIG. 5 is a right side elevational view thereof;

CPC F21S 48/00; F21S 48/10; F21S 48/115;

FIG. 6 is a left side elevational view thereof; and,

F21S 48/225; F21S 48/1233; F21S

FIG. 7 is a front side perspective view thereof.

48/1266; F21S 48/1388; F21S 48/2268;

The rear combination lamp is configured to be mounted to

FIGS. 1 to 7, form no part of the claimed design since the

U.S. PATENT DOCUMENTS

mounting structure and support structure are hidden when the

D523,976 S * 6/2006 Pfeiffer D26/28
D528,680 S * 9/2006 Oda D26/28
D538,452 S * 3/2007 Pfeiffer D26/28

rear combination lamp is mounted to the automobile.

In addition, the appearance of the rear side structures of the

rear combination lamp as shown in broken lines in FIGS. 2

to 6 is for purpose of illustrating the boundaries of the

exterior surface of the rear combination lamp, and forms no

part of the claimed design. The rear combination lamp has

a front lens that is transparent such that features behind the

lens are at least partially visible as illustrated.

A second embodiment of our new design includes the mirror

image of the rear combination lamp shown in FIGS. 1 to 7.
